UNITED STATES PATENT OFFICE.

JOSEPH NIERS, OF MILWAUKEE, WISCONSIN.

ADJUSTABLE WINDOW VENTILATOR.

Application filed June 26, 1925. Serial No. 39,720.

This invention relates to adjustable window ventilators.

Objects of this invention are to provide a ventilator which is readily adjustable to different sized windows, which is held in place by the lower sash in a very positive manner, which locks within the slide for the casing, which is of attractive and pleasing appearance, and which may be cheaply produced.

An embodiment of the invention is shown in the accompany drawings, in which:—

Figure 1 is a front view of a portion of the window showing the ventilator in place.

Figure 2 is a transverse sectional view through the window casing looking down upon the ventilator.

Figure 3 is a vertical sectional view through the window and ventilator.

Referring to the drawings, it will be seen that the ventilator comprises a pair of telescopic members indicated at 1 and 2. The member 1 is provided with a rolled portion 3 which slidably engages the beaded portion 4 of the member 2. The lower end of the member 2 is upturned, as indicated at 5, and engages the downwardly turned portion of the member 1. Thus the members 1 and 2 are provided with interengaging portions at their upper and lower edges, which permit expansion and contraction of the ventilator by sliding the members inwardly or outwardly. Each member is provided with triangular end portions 6 which, as may be seen from Figure 2, are provided also with outwardly projecting offset portions 7. This offset portion is adapted to fit within the slide 8 which receives the lower sash 9, with the triangular member 6 contacting with the finishing strip 10 of the window casing.

It is to be noted further that the triangular members 6 are provided with abrupt shoulders or faces 11 which contact with the inner side of the bottom of the lower sash 9.

In using the device, it is merely necessary to slightly raise the lower sash and insert the ventilator. The members 1 and 2 are slid apart until they occupy the position shown in Figure 2 with reference to the

window casing. Thereafter, the lower sash is pulled downwardly until it contacts with the offset portion 7 at which time its inner face will contact with the shoulder or face 11 of the member 6, thus rigidly locking the ventilator in place. It is to be noted also that the lower portion of the ventilator is seated in front of the bottom board 12 of the window casing, as shown in Figure 3, and thus the entire ventilator is rigidly held in place and is firmly locked by the lower sash against any movement whatsoever.

It will be seen, therefore, that a ventilator has been provided for windows which will direct the air upwardly in the approved manner, and which is expandable to fit different sized windows.

Further, it will be seen that a ventilator has been provided which may be securely locked in place by the window sash against motion in any direction and further, it will be noted that the ventilator is of attractive and neat appearance, and may be cheaply manufactured.

Although the invention has been described in considerable detail, it is to be understood that the invention may be variously embodied and is, therefore, to be limited only as claimed.

It is to be noted that the ventilator is weather proof and will guard against the entrance of rain, although the window may be left partly open.

I claim:

A ventilator adapted for positioning within a window casing provided with stops and with a movable sash; said ventilator comprising a pair of metal members, each of said members having a vertical lower portion and having an outwardly extending portion, said members overlapping and having their marginal edges interengaging to permit expansion of said ventilator to fit windows of different sizes with the vertical portions fitting within the window ledge, each of said members having triangular end portions provided with outwardly projecting channels adapted for positioning between the stops of the window casing and having abrupt upper shoulders adapted to be en-

gaged by the window sash, and having vertical faces above the said shoulders contacting with the inner face of the window sash, said channels having outwardly extending lips fitting over the said stops whereby said window ventilator may be adjusted to the desired width with the channel members in position between the stops and may be

retained by the joint action of the stops and the window sash.

In testimony that I claim the foregoing I have hereunto set my hand at Milwaukee, in the county of Milwaukee and State of Wisconsin.

JOSEPH NIERS.
